UNITED STATES PATENT OFFICE.

HENRY B. DIERDORFF, OF COLUMBUS, OHIO, ASSIGNOR TO THE JEFFREY MANUFACTURING COMPANY, A CORPORATION OF OHIO.

MINING-MACHINE.

1,162,142.

Specification of Letters Patent. Patented Nov. 30, 1915.

Application filed July 30, 1909. Serial No. 510,493.

To all whom it may concern:

Be it known that I, HENRY B. DIERDORFF, a citizen of the United States, residing at Columbus, in the county of Franklin and State of Ohio, have invented certain new and useful Improvements in Mining-Machines, of which the following is a specification, reference being had therein to the accompanying drawing.

10 This invention relates to improvements in mining machines and has to do especially with that class of machines used for undercutting the coal so that it can be blasted or broken down in shape to be loaded upon 15 cars and removed from the mine. It is desirable that a machine of this character should cut a kerf as thin as possible in order that the waste of coal may be reduced to a minimum, and in practice machines of the 20 kind in question do cut a relatively thin kerf. For this reason it is found in the working of coal under certain conditions that the blasting is not effective to break up the body of the coal and expose it so that it 25 can be conveniently attacked for loading. On the contrary, it frequently happens under such conditions as are referred to that the blast merely cracks the body of the coal somewhat and forces it down *en masse*. To 30 obviate this difficulty, what is known as "snubbing" has been more or less commonly practised hitherto. That is to say, after the coal has been undercut by the formation of a substantially horizontal, straight, parallel 35 sided kerf, the miners by means of a pick or other suitable tool cut away or bevel off the coal at the corner formed by the intersection of the coal face and the upper side of the horizontal kerf. In this way the thickness 40 of the kerf is increased at the face of the coal and backward into the coal for a part of the depth of the kerf. Consequently the coal when blasted, or at least the forward part of the mass, has a greater drop, and as 45 a result the blast is more effective in breaking up the coal and rolling it out into the open.

The object of this invention is to provide a mining machine by means of which the 50 coal may be undercut in such a way as to attain the result that has heretofore been reached by means of hand labor in the manner described.

In the accompanying drawings, Figure 1

is a plan view of a mining machine embodying my invention; Fig. 2 is a side elevation of the machine; Fig. 3 is a side elevation of the machine with its front part elevated for the purpose of cutting the auxiliary kerf; Fig. 4 is a transverse section taken on the line 4—4 of Fig. 1; Fig. 5 is a fragmentary side elevation of the devices employed in lifting the front part of the mining machine; Fig. 6 is a section taken transversely to the face of the coal to show the standard form of kerf cut by mining machines; Fig. 7 is a similar section showing the form of kerf cut by my improved machine; and Fig. 8 is a section through the coal parallel with the face thereof, illustrating one method of undercutting the coal with my machine.

While my invention is not restricted to any particular type of machine it is especially adapted for use in connection with undercutting machines of the breast type and it will be noted that I have shown it embodied in this kind of machine.

Referring to the construction of the machine, 1 designates the bed frame as an entirety, the same being provided with the front longitudinal angle bars or supporting elements 2, 2, which are flared at their lower ends as indicated in Fig. 1. The frame comprises the upper longitudinal bars, 3, 3, the upright bars or plates 4, 4, by which the upper bars 3—3 and lower longitudinal bars or supporting elements 2—2 are rigidly connected, the rear transverse rod 5 and the front transverse bar 6 which rigidly connect the upper bars 3, 3, and the transverse bar or frame 7. The frame 7 which is preferably in the form of a casting, comprises the lower horizontal part 7^a, the vertical end parts 7^b, 7^b, and the upper inturned horizontal parts 7^c, 7^c. The lower bars 2, 2, of the frame are rigidly secured to the lower part of this frame 7 and the bars 3, 3, are similarly secured to the upper parts 7^c of said frame.

Upon the bed frame is mounted a carriage 100 which may be of any preferred construction and which I need not, therefore, describe in detail. Suffice it to say that in the machine shown the carriage comprises the rear motor and gearing platform 8, and a forwardly extending cutter frame 9 on which is operatively mounted a suitable cutter chain 10. On the platform 8 is mounted a motor 11

and suitable gearing designated as an entirety by 12, by means of which the motor drives the cutter chain and causes the carriage to move forward or backward on the bed frame.

On the frame or casting 7 is mounted a U-shaped bar 13, the middle horizontal part 13^a of which rests upon the ground and constitutes a supplemental supporting element or a skid for the front part of the bed frame. The upturned ends 13^b, 13^b of the bar 13 slidably engage the upright part 7^b of the frame 7, and are suitably maintained in position by clips 14, 15, which are bolted 10 to the frame 7. Each of the upright parts 13^b is formed with two series of ratchet teeth 16, 17, respectively.

On each of the upright parts 7^b of frame 7 is pivoted a lever socket 18 which carries 20 a pawl 19 disposed in position to engage the teeth 16 of the bar 13. A spring 20 interposed between the socket 18 and the free end of the pawl 19 tends to hold the latter in engagement with the teeth 16. The socket 25 18 is designed to receive a handle or lever bar 21, by means of which the socket may be oscillated to raise and lower the pawl 19.

22 is a gravity detent pivotally mounted on the part 7^b of frame 7 in position to engage 30 the teeth 17 of bar 13 and coöperate with the actuating pawl 19.

This construction being provided in duplicate at either side of the bed frame of the machine, it is clear that the pawls 19 35 may be actuated so as to force the bar 13 downward step by step relative to the bed frame, thus raising the latter off the ground to a desired height where it is held by the action of the pawls 19 and detents 22 in 40 engagement with the teeth 16 and 17.

The machine is provided with suitable jacks 23 and 24 at the front and rear ends respectively of the bed frame.

In the use of a machine of the character 45 shown and described, assuming that it has been brought into the room and disposed adjacent one of the ribs, the operators proceed first to lift the front end of the bed frame by means of the actuating pawls. 50 When the front end of the frame has been raised to a suitable height, and this will depend upon the thickness of the kerf which the machine cuts, the operators proceed to secure the frame rigidly in position by 55 means of the jacks. The motor is started and a partial cut, indicated by *a* in Figs. 7 and 8, is made. The carriage is then retracted, the front end of the bed frame lowered to its normal position and the machine 60 again secured by the jacks. And then a second cut *b* of full depth is made. After which the carriage is again retracted and

the machine moved laterally along the face of the coal for the next cut.

It will be understood that when my invention is used in connection with mining machines of other types other methods of use can be followed according to the character of the machine and the nature of the work.

Referring to Fig. 7, it will readily be seen that the kerf which is thus secured is of the normal thickness in its rear part but of approximately double thickness at its front part. It will be obvious to one familiar with the art that the method of using my improved machine can be varied to a considerable extent. In some cases it may be desirable to cut a continuous kerf across the room of the form shown in Fig. 7, in order to secure a sufficient drop for the coal to insure its being suitably broken up and separated by the blasting. In many cases, however, it is found sufficient to make the shallow upper cut *a* only at intervals across 85 the face of the coal, as indicated in Fig. 8 of the drawing. In any case, it is clear that the desired form of kerf is produced in a simple and efficient manner by a machine embodying my improvements. I prefer to 90 cut the shallow upper kerf as above described. But it will be understood the lower kerf might be cut first.

What I claim is:

1. In a mining machine, the combination 95 of a bed frame, a carriage comprising cutter mechanism mounted to move forward and backward on said frame, means for lifting the front end of the frame comprising a skid arranged transversely beneath the frame, and means mounted on the frame adjacent the skid adapted to operatively engage the latter, and jacks for securing the frame in adjusted position, substantially as and for the purpose set forth.

2. In a mining machine, the combination 100 of a bed frame, a carriage comprising cutter mechanism mounted to move forward and backward on said frame, and means for lifting the front end of the frame comprising a skid having a transverse part disposed beneath the bed frame and up-standing end parts adjacent the sides of the bed frame and slidably secured thereto, and means on the bed frame adapted to engage the up-standing ends of the skid to elevate the frame, substantially as and for the purpose set forth.

In testimony whereof I affix my signature, in presence of two witnesses.

HENRY B. DIERDORFF.
